Des. 186,590
Patented Nov. 10, 1959

186,590

FOOD SERVICE WAGON

William H. Frick, Cleveland, Ohio

Application November 19, 1957, Serial No. 48,543

Term of patent 14 years

(Cl. D14—3)

Fig. 1 is a perspective view of a food service wagon, embodying my new design; and

Fig. 2 is a top plan view.

The rear not shown is plain and the undisclosed end is like the end shown.

I claim:

The ornamental design for a food service wagon, as shown and described.
